UNITED STATES PATENT OFFICE.

CHARLES FREDERICK WILLIAMS, OF WALLINGFORD, CONNECTICUT, ASSIGNOR TO
R. WALLACE & SONS MANUFACTURING COMPANY, OF WALLINGFORD, CONNECTICUT, A CORPORATION OF CONNECTICUT.

TABLE-CABINET.

1,176,259.

Specification of Letters Patent.

Patented Mar. 21, 1916.

Application filed July 14, 1915. Serial No. 39,726.

To all whom it may concern:

Be it known that I, CHARLES F. WILLIAMS, a citizen of the United States of America, residing at Wallingford, Connecticut, have 5 invented a new and useful Table-Cabinet, of which the following is a specification.

The main object of my invention is to provide for valuable table-ware a safe and yet convenient repository which is also of 10 general household utility.

It has been customary to keep silverware such as knives, forks, spoons, etc. in chests, safes, side-boards and ordinary drawers but these all have their objections. They are all 15 obvious storage places inviting immediate examination and plunder.

To solve the difficulty I have constructed a table with secret compartments and drawers. The table is suitably designed for use 20 for instance as a simple serving table. One side of the apron is hinged along the bottom edge and provided with a concealed lock and bolt. When this section of the apron is unlocked and dropped down the compartments and drawers beneath the top are 25 revealed. The apron is preferably provided with supports at the ends so that it can be used as a shelf when let down.

Figure 1, is a perspective view of a construction embodying my invention with the movable apron section down and the compartments and drawers exposed. Fig. 2, is a front view, part of the movable apron being broken away. Fig. 3, is a side view 35 showing in dotted lines, the movable apron section let down as a shelf. Figs. 4 and 5 are fragmentary vertical sectional views showing the locking bolt construction.

The top 10 is fixedly supported upon the 40 legs 11-11, and 12-12. In the design shown the front legs are nearer together than the back legs and this forms a particularly convenient arrangement and appearance for the purpose of my invention.

An apron or shield extends downward 45 from the top between the legs and in the form shown consists of the front section 13, the rear section 14 and the two end sections 15, 15. The bottom 16 corresponds in shape to the top 10 and is secured to the legs to stiffen the construction. The top, bottom and apron form an inner compartment for storage purposes. This compartment is normally closed and the construc- 50

tion and appearance is such that no idea is 55 conveyed to the observer of its being other than an ornamental stand or table. The front apron section 13 however, is hinged along the bottom edge at 17 and provided with one or more locking bolts such as 18. 60 This bolt is located in a passage entirely concealed in the center of the apron and may have its upper end protruding into a socket 19 in the under side of the top 10.

The lower end of the bolt is guided in 65 the socket 20 in the bottom of the apron. A pin 21 projecting from the bolt normally rests in the shallow notch 22 in the upper edge of the socket 20 so as to hold the parts locked. A spring 23 is preferably provided 70 for normally pressing the bolt downward so that the pin 21 rests in the notch 22. Adjacent the notch 22 is another deeper notch 24 adapted to receive the pin 21 when the bolt is turned a part revolution, left- 75 handed from the position shown in Fig. 5 to the position shown in Fig. 4. When the bolt is turned in this direction the spring 23 retracts it and unlocks the apron. The lower end of the bolt 18 may be suitably 80 shaped at 25 for engagement by means of any suitable form of key for operating. When the bolt is in the position shown in Fig. 4 the apron may be tilted forward 85 about the axis of the hinge 17 into the position shown in full lines in Fig. 1 and indicated in dotted lines in Fig. 3, in which position the bolt head will stand retracted thus avoiding any projection that might catch or tear the clothing of a passer-by. 90

The interior of the cabinet may be divided into one or more compartments, for instance, by means of partitions such as 26. One or more drawers such as 27 may be provided for convenience in storage and access. The apron section 13 when let down in the position shown in Fig. 1 may serve as a convenient shelf for the sorting of the silverware. This shelf may also serve as an additional support for dishes, etc. when 100 the construction is being used as a serving table for which it is particularly adapted. The shelf may be additionally supported by one or more slides such as 28 if desired. An abutment 29 may be provided for the 105 edge of the apron in its closed position.

The construction may be made of any suitable material and given such outward

ornamentation or finish as suitable for the conditions under which it is to be used.

From the foregoing it will be seen that the construction of my invention is suitable for use not only as an ordinary stand but as a serving table as well as a safe or repository for valuable property such as table-ware etc.

What I claim is:—

- 10 1. A storage cabinet comprising, a top and legs, an apron depending from the top and between said legs, the front of said apron being designed to swing outwardly and downwardly, a bolt extending upwardly through said hinged front, a socket in the underside of the top to receive the end of said bolt, and means accessible at the lower edge of said front for operating said bolt, said means being concealed from view from the front.
- 15 2. A storage cabinet in the form of a table including a top and legs, an apron depending from said top and between said

legs, one section of said apron being hinged adjacent its lower edge, a bolt extending 25 edgewise through said section, one end of said bolt being exposed at the upper edge with means accessible at the lower edge for operating the bolt, the lower end of said bolt and operating means therefor being 30 concealed in the hinged apron section.

3. A storage cabinet in the form of a table including a top and legs, an apron depending from said top and between said 35 legs, one section of said apron being hinged adjacent its lower edge, a bolt extending edgewise through said section, one end of said bolt being exposed at the upper edge with means accessible at the lower edge for operating the bolt, the lower end of said bolt and said operating means being concealed 40 in said hinged portion of said apron, and with means for holding said hinge section in a substantially horizontal plane when said section is swung outwardly.

CHARLES FREDERICK WILLIAMS.
